CLAIM

We claim the ornamental design for a powered air inflator, as shown.

DESCRIPTION

FIG. 1 is an orthogonal view of a powered air inflator comprising a first embodiment of the ornamental design of the present invention;

FIG. 2 is a side view of the inflator of FIG. 1, the opposite side view being a mirror image;

FIG. 3 is a front view of the inflator of FIG. 1;

FIG. 4 is a rear view of the inflator of FIG. 1;

FIG. 5 is a top view of the inflator of FIG. 1;

FIG. 6 is a bottom view of the inflator of FIG. 1;

FIG. 7 is an orthogonal view of a powered air inflator comprising a second embodiment of the ornamental design of the present invention;

FIG. 8 is a side view of the inflator of FIG. 7, the opposite side view being a mirror image;

FIG. 9 is a front view of the inflator of FIG. 7;

FIG. 10 is a rear view of the inflator of FIG. 7;

FIG. 11 is a top view of the inflator of FIG. 7; and,

FIG. 12 is a bottom view of the inflator of FIG. 7.

The broken line showings in the drawings are for illustrative purposes only and form no part of the claimed design.
